UNITED STATES PATENT OFFICE.

D. VAN HOUTEN, OF FULLERS CORNERS, INDIANA.

IMPROVEMENT IN HORSE-POWERS.

Specification forming part of Letters Patent No. 37,713, dated February 17, 1863.

To all whom it may concern:

Be it known that I, D. VAN HOUTEN, of Fullers Corners, in the county of Whitley and State of Indiana, have invented a new and Improved Horse-Power; and I do hereby declare that the following is a full, clear, and exact description of the same, reference being had to the accompanying drawings, making a part of this specification, in which—

Figure 1 is a side sectional view of my invention, taken in the line $x x$, Fig. 2. Fig. 2 is a plan or top view of the same.

Similar letters of reference indicate corresponding parts in the two figures.

The object of this invention is to obtain a horse power of simple construction, with its parts arranged in such a manner that a high speed will be given the shaft from which the power is taken, and within a very limited space, so that a very compact and portable machine will be obtained, at the same time a durable one.

The invention is more especially designed for driving threshing-machines, but may be advantageously used for other purposes.

To enable those skilled in the art to fully understand and construct my invention, I will proceed to describe it.

A represents the frame of the horse-power, which may be of rectangular form, and provided, if desired, with sides to inclose the principal working parts of the device.

B is a shaft which is placed vertically in the frame A, its lower end being stepped in a cross-piece, a, and its upper part fitted in a bearing, b, in a cross-piece, c, of the frame. On the upper end of this shaft B the driving-wheel C is secured, said wheel being above the frame A. In the frame A, near one end of it, there is placed another vertical shaft, D, the lower end of which is stepped in a cross-piece, d, of the frame A, and its upper part fitted in a bearing, e, in a cross-piece, f. On the upper part of this shaft D, below its bearing e, there is placed and firmly keyed a pulley, g, of small diameter, around which and the driving-wheel C a belt, E, passes.

F is a vertical shaft which is placed in the frame A, near the shaft B, between it and the shaft D, but much nearer the former than the latter. The lower end of the shaft F is stepped

in a cross-piece, h, of the frame A, and its upper part is fitted in a bearing, i, in a cross-piece, j. On this shaft F there is placed a pulley, G, of small diameter, around which a belt, H, passes, said belt also passing around a pulley, I, on the shaft D, the pulley I being considerably larger in diameter than G. On the shaft F there is also placed a bevel-wheel, J, which gears it to a bevel-pinion, K, on a horizontal shaft, L, the latter passing through one of the sides of the frame A, and having a pulley, M, on its outer end. (See Fig. 2.) The belt E, which passes around the driving-wheel C of shaft B and the pulley g of shaft D, passes between idle-pulleys N N, which are fitted on slides O, placed on cross-bars P P on the frame A, the slides being secured at the desired point by bolts or screws k. The idle pulleys N N give the belt E a good bearing around the pulley g, and admit of said belt being tightened when necessary, as will be seen by referring to Fig. 2. The power is taken from the shaft L, and the horse or horses are connected to sweeps which are attached horizontally to the wheel C. These sweeps are not represented, as they are an old and well-known device, and may be seen on many horse-powers in common use.

By this arrangement of the several parts, as herein described, it will be seen that a high speed is transmitted to the shaft L from the wheel C by a very compact mechanism. The shaft L, from which the power is taken, is quite close to the shaft B, on which the power or driving wheel C is placed, and this is effected by a very simple arrangement of the pulleys, shafts, and belts, as set forth.

Having thus described my invention, what I claim as new, and desire to secure by Letters Patent, is—

The arrangement of the four shafts B, D, F, and L, provided, respectively, with the wheels C, pulleys g I, pulley G, and bevel-wheel J, and the bevel-pinion K and pulley M, in connection with the belts E H, to form a new and improved horse-power, as herein set forth.

D. VAN HOUTEN.
